RECEPTACLE HANDLE

Robert H. Lewis, Akron, Ohio, assignor to Firestone Battery Company, Akron, Ohio, a corporation of Delaware

Application July 3, 1933, Serial No. 678,765

3 Claims. (Cl. 16—125)

This invention relates to receptacles having one or more handles, and more especially it relates to receptacles composed of molded material and having removable metal handles secured thereto.

The invention is of primary utility in battery jar construction, wherein the large compartment jars are of such great weight as to make it impractical to mold the handles integral therewith. 10 This invention is an improvement of the construction covered by my Patent No. 1,903,185 granted March 28, 1933.

The chief objects of the invention are to provide an improved metal handle for molded receptacles, 15 which handle will have greater strength than similar handles heretofore provided; to avoid loosening of the handle after it is once applied to the receptacle; to provide a handle which does not materially increase the overall length of the receptacle; and to provide a handle that includes a bail, and so constructed that when used on battery jars the bail cannot fall onto the battery terminal and short-circuit the same. Other objects 20 will be manifest in the following specification.

25 Of the accompanying drawing:

Figure 1 is an end elevation of a receptacle constituting one embodiment of the invention;

Figure 2 is a section on the line 2—2 of Figure 1;

30 Figure 3 is an end elevation of another embodiment of the invention; and

Figure 4 is a section on the line 4—4 of Figure 3.

In the illustrative embodiment shown in Figures 1 and 2 of the drawing, the receptacle 20 is a compartment battery jar composed of molded dielectric material such as hard rubber, asphaltum, or other suitable composition, and 21 is a handle mounted upon the upper marginal portion of one of the end walls thereof. The external face of 35 said end wall is formed with a rectangular recess 22 therein near the top thereof, said recess having its upper margin, at least, slightly undercut as shown at 23, Figure 2. The inner face of the end wall is recessed or rabbeted at 24, at the upper 40 margin thereof.

The handle 21 comprises a small sheet of metal bent upon itself to provide leg portions 21a and 21b and is provided with a cylindrical rod or bar 25 that has its end portions clamped in the loops 50 of the metal at the juncture of leg portions 21a, 21b, and is formed with end flanges 25a, 25a disposed outside said loops. The respective leg portions 21b are connected by a web 21c at their lower ends, and the leg portions 21a are connected by 55 a web 21d.

The leg portions 21a are generally parallel to the leg portions 21b, and are spaced apart therefrom, the lower end portion of each leg 21a being bent at right angles to provide a horizontal portion 21e, which portion is formed with a downwardly extending end portion 21f, the end portions 21f being connected by web 21d. The web 21d is positioned in recess or rabbet 24 formed in the front face of the end wall of receptacle 20, the leg portions 21f extending somewhat above the top of the receptacle so that horizontal leg portions 21e are spaced substantially above the top of the receptacle. 5

The members 21a, 21b of each pair of legs are drawn toward each other, to cause the handle structure firmly to grip the receptacle 20 and the hand-grip bar 25, by means of a bolt 26 that extends through suitable apertures in leg portions 21f and 21b and is provided on its end with a nut 27. The bolts 26 are disposed below horizontal leg portions 21e, and overlie the upper margin of the receptacle. The leg portion 21b of the handle may be formed with marginal reinforcing ribs 29, 29 as shown. The lower margin of web 21c is formed with a pair of spaced apart angularly directed flanges or hooks 21g which engage the undercut margin 23. In this embodiment of the invention, strains imposed upon the handle incidental to clamping the receptacle in a vehicle are taken by bolts 26 and rod 25. The bolts 26 20 easily resist such strains by reason of the support furnished them by the receptacle structure, and the rod 25 is easily replaced if it should become 25 bent.

The leg members 21a, 21b are sufficiently resilient to flex somewhat under the action of the bolt 26, with the result that subsequent slight loosening of the screw will not cause the leg members to become loose on the receptacle. The parallel spaced arrangement of the legs 21a, 21b of the 30 handle and the reinforcing of the legs by the bolt 26 prevents rattling of the handle and provides a truss effect that adds greatly to the lateral rigidity of the handle so that the latter is not easily 35 accidentally bent. 45

In the embodiment of the invention shown in Figures 3 and 4, the receptacle 30 is similar to receptacle 20 previously described, and is formed with a similar recess 31. The handle structure 32 differs from that previously described in that 40 it comprises a hand grip portion consisting of a pivotally mounted bail 33. The bail consists of a metal rod that has its end portions 33a, 33a 45 reversely bent so as to be directed toward each other as shown, each of said bends being a com- 50

bound curve so that there is a horizontally disposed portion 33b that is relatively near the end portion 33a as compared to the major horizontal portion of the bail where it is gripped by the hand.

The bail is connected to the handle structure by means of its end portions 33a which are pivotally mounted in the loops or bends 34, 34 formed at the juncture of leg portions 32a, 32b of the handle structure. Said leg portions are substantially parallel, and are drawn firmly into engagement with the receptacle 30 by means of bolts 35, 35 provided with respective nuts 36, said bolts resting upon the top margin of the receptacle. The bends or loops 34 are not of semicircular contour, but are arcuate contiguous with leg portion 32b, and are straight and downwardly sloped therefrom toward leg portion 32a. The arrangement is such that if the bail 33 falls toward the top of the receptacle, bail portions 33b will engage the straight sloped portions of the bends 34, as is shown in broken lines in Figure 4, and thereby support the bail in an inclined position so that it will not rest upon the terminals of a battery, when the handle is used on a battery jar.

The usual webs that connect the respective leg portions 32a, 32a and 32b, 32b of the handle are so constructed as to be positioned below the top margin of the receptacle 30 when the handle is mounted thereon, so that clamping means for holding the receptacle in a vehicle may engage the top margin of the receptacle as is shown in broken lines at 38, Figure 3.

The invention provides a simple and strong handle for receptacles, and achieves the other objects set out in the foregoing statement of objects.

The invention may be otherwise modified without departing from the spirit of the invention or the scope of the appended claims.

What is claimed is:

1. A handle for a battery box having an upwardly extending portion above an upper edge thereof and a recess on an outer face thereof below said upwardly extending portion, said recess defining a shoulder, said handle comprising a plurality of metallic loops, a hand-grip bar mounted through said loops, said loops being provided with downwardly extending inner and outer leg members, said members being spaced apart, said inner leg members having a downwardly extending portion for engaging the inner face of said upwardly projecting portion of the box above the upper edge of the latter, said outer leg members having a portion thereon for engaging below the shoulder on the outer face of the box, and a bolt extending through the leg members for drawing said legs toward each other tightly against the box, said leg members being spaced

apart sufficiently to permit tightening of said bolt so as to spring said leg members without contacting one another, whereby the bolts will not loosen under vibration.

2. A handle for a battery box comprising a pair of metallic loops each being formed with a top portion defining an abutment, and a bail having its end portions swivelled in said loops for pivotal movement, whereby the overall height of the battery box and handle may be reduced by swinging the bail to one side or the other, the bail end portions which are swiveled in the loops being bent toward each other, and the free portion of the bail being formed with a curved portion relatively close to said end portions as compared to the remaining hand grip portion of the bail, whereby said relatively close curved portions will engage said abutments on the loops and movement of the bail toward the top of the battery will be limited to prevent short circuiting of the terminals thereof by the bail, said loops being provided with downwardly extending, spaced apart leg members for engaging the box, and a bolt extending through each of the leg members for drawing said legs toward each other tightly against the box, said leg members being spaced apart sufficiently to permit tightening of said bolt so as to spring said leg members without contacting one another, whereby the bolts will not loosen under vibration.

3. A handle for a battery box having an upwardly extending portion above an upper edge thereof and a recess on an outer face thereof below said upwardly extending portion, said recess defining a shoulder, said handle comprising a plurality of metallic loops and a bail having its end portions swivelled in said loops, said loops and said bail ends being formed with abutments so that the loops limit the movability of the bail over the battery box to prevent short-circuiting of the terminals thereof by the bail, said loops being provided with downwardly extending inner and outer leg members, said members being spaced apart, said inner leg member having a downwardly extending portion for engaging the inner face of said upwardly projecting portion of the box above the upper edge of the latter, said outer leg member having a portion thereon for engaging below the shoulder on the outer face of the box, and a bolt extending through the leg members for drawing said legs toward each other tightly against the box, said leg members being spaced apart sufficiently to permit tightening of said bolt so as to spring said leg members without contacting one another whereby the handle will not rattle on the box and whereby the bolts will not loosen under vibration.

ROBERT H. LEWIS.
